UNITED STATES PATENT OFFICE.

ALFRED COUSEN, OF DETROIT, MICHIGAN.

DESIGN FOR A POT OR JAR.

SPECIFICATION forming part of Design No. 19,609, dated January 28, 1890.

Application filed December 14, 1889. Serial No. 333,817. Term of patent 7 years.

To all whom it may concern:

Be it known that I, ALFRED COUSEN, a citizen of Great Britain, residing at Detroit, in the county of Wayne and State of Michigan, 5 have invented certain new and useful Improvements in a Design for Pots and Jars, of which the following is a specification, reference being had therein to the accompanying drawings.

10 This invention relates to a new and useful design for flower-pots, jardinières, and vases.

My invention refers more particularly to that class of articles represented in plastic material, such as cement or clay.

15 In the drawings, A is the body of the pot to which my ornamentation is applied. This pot is formed in the usual way, and it expands from the bottom upward in a larger degree than the ordinary pot and upon curved

20 lines until to about the center of its height, when it begins to contract again gradually more abruptly until it regains the dimensions of the bottom, or nearly so, when it continues

upward into a conically-flaring rim B of short height. The pot is supported on short legs C, 25 which, with the body, are completely decorated, as shown, with irregular curves or scrolls, forming artistic florations. On or near the center of the body portion is formed in relief a representation of a branch having leaves 30 and fruit thereon.

By the above representations and formations a very ornamental and artistic article is produced.

Having thus fully described my invention, 35 what I claim, and desire to secure by Letters Patent, is—

The design for a pot or jar, substantially as herein shown and described.

In testimony whereof I affix my signature, 40 in presence of two witnesses, this 24th day of May, 1889.

ALFRED COUSEN.
